UNITED STATES PATENT AND TRADEMARK OFFICE
CERTIFICATE OF CORRECTION

PATENT NO. : D743,303 S
APPLICATION NO. : 29/506102
DATED : November 17, 2015
INVENTOR(S) : Yong Huang et al.

Page 1 of 1

It is certified that error appears in the above-identified patent and that said Letters Patent is hereby corrected as shown below:

Title page, item 71, Line 2, after “Baoding” insert -- City --.

Title page, item 72, Line 1, after “Baoding” insert -- City --.

72, line 2, after “Baoding” insert -- City --.

72, line 3, after “Baoding” insert -- City -- (both occurrences).

72, line 4, after “Baoding” insert -- City --.

72, line 5, after “Baoding” insert -- City --.

72, line 6, after “Baoding” insert -- City --.

72, line 7, after “Baoding” insert -- City -- (both occurrences).

72, line 8, after “Baoding” insert -- City --.

Title page, item 73, line 2, delete “Boading” and insert in its place -- Baoding City --.

Signed and Sealed this
